UNITED STATES PATENT OFFICE

JOSEPH H. C. HIRD, OF MILLER, NEBRASKA.

ROAD-MACHINE.

1,175,263.

Specification of Letters Patent. Patented Mar. 14, 1916.

Application filed April 10, 1915. Serial No. 20,499.

To all whom it may concern:

Be it known that I, JOSEPH H. C. HIRD, a citizen of the United States, residing at Miller, in the county of Buffalo and State 5 of Nebraska, have invented certain new and useful Improvements in Road-Machines, of which the following is a specification, reference being had to the accompanying drawings.

10 This invention comprehends certain new and useful improvements in road making and repairing machines, and relates particularly to scrapers of the wheeled type.

The invention has for its primary object 15 a durable and efficient construction of machine of this character embodying a novel and useful construction and arrangement of the parts of the blade elevating and lowering mechanism, and a novel and useful construction and arrangement of the parts relating to the means for tilting the blade or 20 scoop to dump the same.

A further object of the invention is a road 25 scraping machine in which the operating levers are all arranged within convenient reach of the operator upon a seat carried by the wheel supported framework, both of said levers being arranged upon one side of said seat whereby they may be operated by 30 one hand of the operator or attendant, while his other hand will be free to guide the horses or for other purposes. And the invention also aims to generally improve machines of this character so as to render them 35 more useful and commercially desirable.

With these and other objects in view, as will more fully appear as the description proceeds, the invention consists in certain constructions, arrangements and combinations 40 of the parts that I shall hereinafter describe and claim.

For a full understanding of the invention, reference is to be had to the following description and accompanying drawings, in 45 which,

Figure 1 is a side elevation of a road machine embodying the improvements of my invention. Fig. 2 is a top plan view of a portion of the machine, parts being shown 50 in section. Fig. 3 is a fragmentary transverse vertical section through the machine. Fig. 4 is a detail horizontal section on the line 4—4 of Fig. 1. Fig. 5 is a detail perspective view of a guide bracket hereinafter

referred to, and Fig. 6 is a similar view of 55 a roller supporting shaft used in connection with said bracket.

Corresponding and like parts are referred to in the following description and designated in all of the views of the accompanying 60 drawing by like reference characters.

Referring to the drawings, the numeral 1 designates as a whole the wheel supported framework which is of the elevated type and supported at one end upon a front axle 2 65 which may be connected to a pole or tongue 3 that may be arranged for any desired number of horses, according to the work in hand, the framework being supported at its other end upon the rear axle 4.

Pivotaly mounted upon the rear axle 4 at the ends thereof and outside of the rear ground or traveling wheels 5, are longitudinally extending arms 6, said arms extending forwardly from said axle underneath 75 the framework, as clearly illustrated in the drawings, suspending the blade or scoop 7 at their forward ends. Preferably, an inner pair of arms 8 is also provided, said arms being pivotally mounted at their rear ends 80 on the axle 4 and prevented from sidewise movement by collars 9 or similar devices, the forward ends of the inner arms 8 being connected to a transverse brace bar 10 which extends from one of the outer arms 6 to the other. The inner arms 8 may be braced in any desired way as, for example, by the rearwardly converging braces 11 which are secured to the inner arms near the forward ends of the latter and to a bracket 12 which 90 is secured to or formed as part of a clip 13 mounted upon the rear axle 4 at the middle thereof.

Contractile springs 14 are secured in any desired way to a transversely extending bar 95 15 which forms part of the framework, said springs extending forwardly and downwardly from the bar 15 and being connected at their forward lower ends to the transversely extending brace bar 10 above referred to, preferably at points where the inner arms 8 are connected to this bar. The springs 14 exert a tension to hold the arms 6 and 8 in their elevated positions so as to hold the scoop 7 raised and inoperative, 105 and in order to move the scoop downwardly, I have provided a lever 16 which is fulcrumed intermediate of its ends upon a

stand 17 mounted on top of the framework 1, said lever being provided with the ordinary spring pressed detent, designed for engagement with a toothed quadrant 18 and being pivotally connected at its rear end to the upper ends of laterally and downwardly inclined suspension bars 19. The outer lower ends of the bars 19 are connected to vertically disposed link rods 20, and the lower ends of said link rods are pivotally connected to the outer arms 6 near the forward ends of the latter, whereby it will be understood that when the lever is manipulated and moved in a direction to press downwardly upon the suspension bars 19, the arms 6 and 8 will be moved downwardly and the scoop 7 will be brought down to the ground and to its operative position, where it may be held by the engagement of the detent of the hand lever with the quadrant 18. Just as soon as the detent is released the springs 14 will be permitted to act to again raise the scoop to its inoperative position. To assist in guiding the parts in these movements and to facilitate the operation, substantially U-shaped brackets 21 are connected to the bars 19 and link rods 20 at their points of juncture, the side members 22 of said brackets extending outwardly in a lateral direction and supporting rollers 23 which are adapted to roll along the outer faces of longitudinally spaced braces 24 that form part of the main framework 1 and that extend forwardly and thence upwardly and inwardly where they are connected at their upper ends to one of the longitudinal upper sills 25 of the framework, and the shaft 26 which carries these rollers 23 is preferably formed at its middle, between said rollers, with a block 27 through which extends the rod 28 which fastens the bracket 21 to the link rods and suspension bars, the rod 28 passing between the braces 24 just mentioned. The scoop 7 is pivotally mounted at its ends, as at 29, to the forward ends of the outer arms 6 whereby it may tilt about a transversely extending horizontal axis in order to dump its contents, preferably after it has been raised to its elevated and inoperative position, and to tilt and dump the scoop it is in the present embodiment of the invention, provided at an intermediate point with an upwardly extending apertured ear 30; links 31 are pivotally connected at one end to the said ear on opposite sides of the same; and a hand lever 32 is pivotally connected at its lower end to the forward ends of said links, said lever being fulcrumed intermediate of its ends on one of the longitudinally extending sills or beams of the framework, and like the lever 16, being disposed in convenient proximity to the driver's seat 33. The lever 32 is provided with a spring pressed detent designed for engagement with a toothed quadrant 34.

Preferably the lever 32 has its lower arm movable in a guide slot 35 formed in a bar 36 which is secured in the framework.

From the foregoing description in connection with the accompanying drawings, the operation of my improved road machine will be apparent.

In the practical use of the machine, as it is drawn along the road the operator may easily move the scraper down to its operative position in contact with the ground by pulling upward upon the forward or handle end of the lever 16, whereby the arms 6 and 8 will be swung downwardly on the rear axle 4, and the contractile springs 14 stretched. When the parts have been adjusted to the required positions, the spring pressed detent of the lever 15 is engaged with a registering notch or tooth of the quadrant 18. When it is desired to dump the scoop, it is preferably first raised to its inoperative position and the lever 32 is manipulated. As the operator pulls rearwardly upon the upper or handle end of the lever 32 it is obvious that, through the instrumentality of the links 31, the scoop 7 will be tilted and its rear edge raised and front or blade edge lowered, whereby the soil and the like will be discharged therefrom.

While the accompanying drawings illustrate what I believe to be the preferred embodiment of my invention, it is to be understood that the invention is not limited thereto, but that various changes may be made in the details of construction, without departing from the scope of the invention as defined in the appended claims.

What is claimed is:

1. A machine of the character described, comprising a wheel supported framework, including a rear axle, scoop supporting arms pivotally mounted upon said axle, a transversely extending bar connected to said arms in front of the rear axle, a support carried by said arms, contractile springs connected at their lower ends to said bar, and extending upwardly and rearwardly therefrom and connected at their upper ends to the framework, a hand lever mounted on top of the framework, suspension bars connected to said lever and extending outwardly and downwardly therefrom, and link rods connecting the lower ends of said suspension bars to the scoop supporting arms.

2. A machine of the character described, comprising a wheel supported frame, including a rear axle, scoop supporting arms pivotally mounted at their rear ends on said axle and extending forwardly therefrom, a transverse brace bar connecting said arms together, contractile springs connected to said bar and extending upwardly therefrom and connected at their upper ends to the

framework, a hand lever mounted on top of the framework, suspension bars connected to one end of said lever and extending laterally and downwardly therefrom, vertically movable link rods connecting the lower ends of the suspension bars to said arms, U-shaped brackets connected to said suspension bars and link rods, rollers journaled in said brackets and movable upon the framework, work in the upward and downward movements of said link rods, and a scoop carried by said arms.

3. A machine of the character described, comprising a wheel supported framework including a rear axle, scoop supporting arms pivotally mounted at their rear ends on said axle, and extending forwardly therefrom, a scoop carried by said arms, a hand lever mounted on the top of the framework, suspension bars connected at their lower ends to one end of said lever and extending downwardly and laterally therefrom, link rods pivotally connecting the scoop supporting arms and the lower ends of said suspension bars, brackets secured to said link rods, shafts mounted in said brackets and provided intermediate of their ends with lugs, and rollers mounted on said shafts on opposite sides of said blocks and movable upon the framework, the connections between the

link rods and the brackets extending outwardly through said blocks and connected thereto, substantially as described.

4. A machine of the character described, comprising a wheel supported framework, including a rear axle, scoop supporting arms pivotally mounted at their lower ends on said axle and extending forwardly therefrom, a scoop carried by said arms, a hand lever mounted on top of the framework, suspension bars pivotally connected at one end of the lever and extending laterally and downwardly therefrom, link rods pivotally connecting the lower outer ends of said suspension bars to said arms, a support carried by said arms, brackets, shafts mounted in said brackets, rollers journaled on said shafts, the shafts being formed between said rollers with blocks, and connecting rods passing through the suspension bars and link rods and also through said blocks and connected to the latter, as and for the purpose set forth.

In testimony whereof I hereunto affix my signature in the presence of two witnesses.

JOSEPH H. C. HIRD.
